(No Model.)

O. C. BJELLAND.
ATTACHMENT FOR FLOWER POTS.

No. 548.508.

Patented Oct. 22, 1895.

UNITED STATES PATENT OFFICE.

OMMUND C. BJELLAND, OF PORTLAND, NORTH DAKOTA.

ATTACHMENT FOR FLOWER-POTS.

SPECIFICATION forming part of Letters Patent No. 548,508, dated October 22, 1895.

Application filed May 27, 1895. Serial No. 550,848. (No model.)

To all whom it may concern:

Be it known that I, OMMUND C. BJELLAND, a citizen of the United States, and a resident of Portland, in the county of Traill and State 5 of North Dakota, have invented certain new and useful Improvements in Attachments for Flower-Pots; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of a flower-pot with a growing plant supported by my attachment. Fig. 2 is a sectional view of the same on a vertical plane through the middle of the flower-pot and vertical standard forming part of my attachment, showing in dotted lines the adjustment of said standard or support and its adjustable and expandible hoop. Fig. 3 is a transverse sectional view on a horizontal plane through the hoop, as indicated by the dotted line marked $\alpha\alpha$ in Fig. 2. Fig. 25 4 is a detail view of the adjustable lock or catch for fastening the expandible sliding hoop adjustably upon its vertical support, and Fig. 5 is a sectional detail view of the lower end of the vertical standard and the 30 horizontal bracket-arm in which it is fastened adjustably.

Like letters of reference designate corresponding parts in all the figures.

My invention relates to devices or appliances for supporting and sustaining plants growing in a tub, pot, or other similar receptacle; and it consists in the combination, with such a receptacle, of the adjustable supporting device, which will be hereinafter more 40 fully described and claimed.

Referring to the accompanying drawings, the letter A designates a flower-pot, and P a living plant growing in the same. Attached removably and adjustably to one side of the 45 pot or receptacle A is a bracket comprising a horizontal arm B, having a series of transverse screw-threaded apertures $b b$ and a depending flat spike C extending downwardly at right angles to the arm B and having a 50 screw-threaded aperture c near its upper end, in which works the inner end of a thumb-screw D, the threaded shank of which also

works through a threaded aperture e in a depending spring-tongue E, of the configuration shown more clearly in Fig. 5, so that the upper edge of the plant-receptacle A may be clamped firmly between the depending spike C and spring-tongue E by tightening up the thumb-screw D.

In order that the bracket B C E may get a firm bearing upon the upper edge of the receptacle A, the rear end of the horizontal arm B, overlapping the spike C, is made flat and broad, and the spring or tongue E is bent into the configuration shown, so that it may be clamped firmly against the outside of the pot or receptacle by tightening or screwing up the thumb-screw D. The other end of the bracket-arm B overlaps the top of the receptacle A some distance to permit of the adjustment nearer to or farther from the center of the pot of the tubular standard F, into the hollow lower end of which is screwed or soldered, whichever may be most convenient, a solid cylindrical plug F', flattened at its projecting lower end, which has a screw-threaded aperture f , through which is inserted the thumb-screw G, by means of which, in conjunction with any one of the screw-threaded apertures $b b$, said tubular standard F is 70 fastened adjustably and removably upon the horizontal bracket-arm B. By this mode of fastening it will also be seen that the angle of standard F may be changed at will, as indicated by the broken lines in Fig. 2. Upon 75 this standard F, which is circular in cross-section, slides a sleeve H, provided with a spring-catch I, (shown more clearly in the detail view, Fig. 4,) the lip i of which may engage any one of a series of holes $h h$, located 80 in a vertical row, in alignment with one another, on one side of the standard. To release the catch I from the hole h , with which, for the time being, it is engaged or interlocked, it is only necessary to press upon the 85 tail I', which releases the catch, so that it may be slid up or down and again interlocked with the appropriately-selected hole h by letting go of tail I', which permits the lip i to 90 slip into and interlock with the appropriate hole in the standard at any desired distance 95 above the bracket in the receptacle A. Upon this adjustable sleeve H, opposite to its catch or fastening I, is fastened by riveting or 100

soldering a ring or hoop *J*, made preferably of properly-tempered spring-steel, the free ends of which overlap and are confined by loops or keepers *K K*, as illustrated in Fig. 3, so that the elastic hoop *J* may be either expanded or reduced.

In order to hold the hoop in its properly-adjusted position, I provide it with a suitable number of small registering or coinciding apertures *j j* and *k k*, through which may be inserted wire ties *l*, thus insuring that the hoop will be maintained in its properly-adjusted position until this is purposely changed or readjusted.

From the foregoing description, taken in connection with the drawings, the manner of using and adjusting this device will, it is believed, be readily understood. It is fastened to the pot or plant-receptacle *A* on one side thereof, as clearly illustrated in Fig. 2, by means of the thumb-nut *D* and parts *C* and *E*, and the tubular standard *F* is fastened to and adjusted at the proper angle or deflection from the perpendicular by means of the thumb-nut *G* at its lower end.

It will of course be understood that the standard *F* need not be made hollow or tubular, as it may be solid; if desired, but by making it tubular the weight of the attachment as a whole is considerably reduced and its manipulation made easier. After the standard *F* has been properly adjusted and fastened (by screw *G*) in its adjusted position the expandible hoop *J* is adjusted at the proper elevation upon standard *F* and fastened thereto by means of the adjustable sleeve *H* and its catch *I*. The last step consists in properly adjusting or regulating the diameter of the hoop *J*, so as to confine within it the side shoots or branches of the plant to any desired extent, after which the hoop is maintained at the proper dimensions by means of

the sliding bands or keepers *K K* in conjunction with the wire locks or ties *l*.

Having thus described my invention, I claim and desire to secure by Letters Patent of the United States—

1. The herein-described adjustable attachment to flower pots, consisting of the bracket comprising the horizontal perforated arm *B*; depending spike *C*, tongue *E* and thumb-screw *D*, in combination with the adjustable standard *F* having apertures *h h*, and sliding sleeve *H* provided on one side with the spring-catch *I* adapted to engage the row of apertures *h* in the standard, and on the opposite or inner side with an expandible and contractible hoop *J*; substantially as and for the purpose shown and set forth.

2. An adjustable support for living plants growing in a movable receptacle *A*, consisting of a bracket adapted to be attached, removably, to one side of the receptacle so as to overlap the upper edge of the same; the tubular and apertured standard *F*, having a solid perforated bearing-plug *F'* inserted into its lower end; the thumb-screw *G* connecting said plug to the apertured horizontal arm of the bracket; the vertically adjustable sleeve *H* constructed as described and provided with the spring-catch *I* having the lip *i* and tail *I'*; and the elastic expandible and contractible hoop *J* provided with the keeper-bands or loops *K K*, apertures *k k* and *j j* and wire ties *l*; all constructed and combined substantially in the manner and for the purpose herein shown and set forth.

In testimony that I claim the foregoing as my own I have hereunto affixed my signature in presence of two witnesses.

OMMUND C. BJELLAND.
